(No Model.)

C. F. KINCHELOE.
HORSE DETACHER.

No. 606,419.

Patented June 28, 1898.

UNITED STATES PATENT OFFICE.

CHARLES F. KINCHELOE, OF WASHINGTON, DISTRICT OF COLUMBIA.

HORSE-DETACHER.

SPECIFICATION forming part of Letters Patent No. 606,419, dated June 28, 1898.

Application filed January 13, 1898. Serial No. 666,567. (No model.)

To all whom it may concern:

Be it known that I, CHARLES F. KINCHELOE, a citizen of the United States, residing at Washington, in the District of Columbia, have 5 invented a new and useful Improvement in Horse-Detachers, of which improvement the following is a specification.

My invention consists of a horse-detacher for detaching horses from vehicles in cases of 10 emergency; and the objects of my invention are, first, to attach the tongue or thills to the vehicle in such manner that they can be readily detached therefrom, and, second, to enable the occupant of the vehicle to quickly 15 and easily detach from the vehicle the tongue or thills, together with the horse or horses attached thereto, in event of said horse or horses becoming unmanageable or other emergency. I attain these objects by the mechanism illustrated in the following drawings, in which—

Figure 1 is a view in perspective of the front axle of the vehicle, showing my improved detaching device attached thereto. Fig. 2 is a 20 detailed view in perspective of a section of the horizontal rotating release-rod with one of the two slotted eye ends of the tongue or thills in place thereon. Fig. 3 is a similar view to Fig. 2, showing the said eye end of the tongue or thills detached from the said 25 release-rod.

Throughout the specification similar letters refer to similar parts.

Referring to Fig. 1 of the drawings, A is the horizontal rotating release-rod, which 30 when in position extends horizontally along and just in front of the front axle of the vehicle and between and through the axle-clips B B and the central support C, thus taking the place of the usual thill-bolts and supporting the tongue or thills in the usual position, as will be seen by reference to Fig. 1.

The principal features of the release-rod A are as follows: First, two thin oval sections i i, which sections are similar to each other 45 and so spaced on the release-rod—one near each end—as to receive and support the rear or eye ends k k of the tongue or thills in the usual positions by means of the slots m m and the slot-expansions n n; second, the lever o, fitting on the release-rod A by means 50 of an eyehole and attached to said release-rod by a set-screw, to which lever o is attached

the operating-cable D, by which the detacher is operated by the occupant of the vehicle; third, the two similar nuts or threaded end 55 caps s s, which fit on the threaded ends of the release-rod and prevent it from shifting endwise.

The part u is a horizontal flat steel spring attached to the central support C in such 60 manner as to press against the flattened under surface v of the lever o, thus preventing the release-rod from rotating without the application of force to the lever by means of the operating-cable D. 65

The other principal and distinguishing feature of my invention is the construction or form of the rear iron eye ends k k of the tongue or thills, said eye ends having horizontal slots m m, which extend forward into 70 said eye ends k k and terminate in peculiarly-shaped slot expansions n n, which take the place of the usual bolt-holes in said eye ends.

The slots m m are just wide enough vertically to allow the thin oval sections i i of the release-rod to pass edgewise through them and into the slot expansions n n, and the slot expansions n n are so shaped that the release-rod on entering them can be rotated only one 75 way and can be rotated in that direction only part way around, and also so that on being rotated back for the purpose of releasing or detaching the tongue or thills said release-rod cannot be rotated beyond the position in 80 which it entered said slot expansions, thus securing absolute certainty of detachment when desired.

When the tongue or thills are attached to the vehicle, as shown in Fig. 1, the release-rod A is fixed in such position that the broad surfaces of the sections i i are presented to the slots m m, thus preventing the tongue or thills from being detached until the release-rod is rotated into such position that the thin 85 sections i i can pass edgewise through the slots m m.

The operation and action of the detacher are as follows: With the detacher in position, as shown in Fig. 1, the operating-cable D is 90 drawn upward, thus rotating the release-rod A into the proper position for the thin sections i i to pass through the slots m m, thus 95 detaching the tongue or thills, together with

the horse or horses attached thereto, from the vehicle.

What I claim as my invention, and desire to secure by Letters Patent, is—

5 1. A detaching mechanism for vehicles, consisting of coupling parts, one on the front axle and one on the shaft or tongue—one part being slotted, combined with a release-rod having a thin part, or section, fitted to the slot, said rod being located in the unslotted part and adapted to receive and, when turned, hold the slotted part; and means for turning said rod, substantially as described.

15 2. A detaching mechanism for vehicles, consisting of two sets of coupling parts, one set on the front axle and one on the shafts or tongue—one of which sets is slotted, com-

bined with a rod the ends of which are supported in the unslotted set of coupling parts, and which rod has thin parts, or sections, 20 adapted to enter the said slots and, when turned, to hold the slotted parts, substantially as described.

3. In combination with the front axle of a vehicle, a rod supported in brackets on said axle and having thin parts, or sections; coupling parts, as *k*, on the tongue or shafts slotted to pass over said thin parts, or sections, and to be held by said sections when turned, substantially as described.

CHARLES F. KINCHELOE.
